UNITED STATES PATENT OFFICE.

JOSEPH E. STRAKER, JR., OF ATTLEBORO, MASSACHUSETTS.

DESIGN FOR A HANDLE FOR SPOONS OR SIMILAR ARTICLES.

SPECIFICATION forming part of Design No. 36,419, dated July 14, 1903.

Application filed May 28, 1903. Serial No. 159,214. Term of patent 7 years.

To all whom it may concern:

Be it known that I, JOSEPH E. STRAKER, Jr., a citizen of the United States, residing at Attleboro, in the county of Bristol and State of Massachusetts, have invented a new, original, and ornamental Design for the Handle of a Spoon or Similar Article, of which the following is a specification, reference being had to the accompanying drawings.

Figure 1 is an obverse view of a spoon on the handle of which is my design, and Fig. 2 shows the reverse side of the spoon.

Having described my invention, what I claim as new, and desire to secure by Letters Patent, is—

The ornamental design for the handle of a spoon or similar article as shown.

In testimony whereof I have signed my name to this specification in the presence of two subscribing witnesses.

JOSEPH E. STRAKER, JR.
